UNITED STATES PATENT OFFICE.

JOHN R. McGIFFERT, OF DULUTH, MINNESOTA, ASSIGNOR TO CLYDE IRON WORKS, OF DULUTH, MINNESOTA, A CORPORATION OF MINNESOTA.

BASE FOR LOG-LOADERS.

No. 822,010.

Specification of Letters Patent.

Patented May 29, 1906.

Application filed December 30, 1904. Serial No. 238,983.

To all whom it may concern:

Be it known that I, JOHN R. McGIFFERT, a citizen of the United States, and a resident of Duluth, county of St. Louis, State of Minnesota, have invented a new and useful Improvement in Bases for Log-Loaders, of which the following is a specification, the principle of the invention being herein explained and the best mode in which I have contemplated applying that principle, so as to distinguish it from other inventions.

My invention relates to bases for log-loading devices, and particularly to bases for that class of log-loading devices in which the loading mechanism is mounted upon a base which is adapted to be mounted upon an ordinary flat or logging car and hauled from car to car, as may be desired, such hauling movement sometimes involving the necessity of moving the base laterally as well as longitudinally—as, for instance, when the cars are standing upon a curve.

The object of my invention is to effect such sliding movement with the expenditure of less power than it has heretofore, in so far as I am aware, required and also incidentally to reduce the wear and tear upon the cars over which the mechanism is transported.

My said invention consists of means hereinafter fully described, and particularly set forth in the claims.

The annexed drawings and the following description set forth in detail certain means embodying my invention, such means constituting but one of the various forms in which the principle of the invention may be used.

In said annexed drawings, Figure 1 represents a plan of a base for supporting log-loading mechanism and embodying my invention, portions of the base being shown broken away to disclose the detailed construction. Fig. 2 represents a vertical central longitudinal section of said base. Fig. 3 represents, upon an enlarged scale, a vertical transverse section taken upon the plane indicated by line 3 3, Fig. 1. Fig. 4 represents a detail section of a part of one of the rollers forming part of the structure embodying my invention, together with a sectional view of one of the bearings for the ends of the roller-spindles, such bearing being shown secured to the frame structure of the base.

The said base consists, primarily, of a

frame structure and a series of traction-rollers mounted thereon, as hereinafter fully described. The frame structure includes two pairs of longitudinal parallel beams, each such pair consisting of an outside main I-beam *a*, preferably provided with upturned ends, as shown, and an inner parallel I-beam *a'* of less depth than beam *a*. Transverse end cross beams *a*² are secured to beams *a* so as to bring their upper surfaces flush with the upper surfaces of said beams *a*, as shown. 55 These beams rest upon the ends of beams *a'*, the lower surfaces of the latter being preferably flush with the lower surfaces of beams *a*. Spaced equidistantly along and riveted to the inner opposing surfaces of the beams *a* and *a'* is a series of bearing members *b*, in which are mounted the ends of horizontal spindles *b'*, upon each of which is mounted a roller *b*². The axes of the set of rollers supported between the one pair of beams *a* and *a'* are inclined relatively to the axes of the rollers supported between the other pair of beams, as shown, and the rollers of the respective sets are parallel with each other. It will therefore be seen that the axes of one set 60 of rollers are inclined in one direction relatively to a central longitudinal plane perpendicular to the plane of the base, and the axes of the other set are inclined relatively to said plane in the opposite direction. The rollers 65 are of a diameter such as to cause them to project below the plane of the lower surface of the frame structure, as shown in Figs. 2 and 3, so that when the base is placed upon the top of a flat or logging car the frame 70 structure will rest upon the rollers and off such car. Suitable cross-braces *a*³ *a*³ are provided for properly strengthening the structure.

As a result of the above-described construction the base may be hauled longitudinally, laterally, or diagonally, and in each case a partial rolling contact is effected which reduces the amount of power required for such hauling as compared with the amount 95 required when pure frictional contact is overcome, as in the case in structures heretofore employed, where side runners are used which rest directly upon the car.

The logging-cars now in general use are not 100 provided with a continuous flooring, but are constructed with a skeleton bed consisting of parallel spaced transverse beams or bunks, as

shown in dotted lines in Figs. 1 and 2. To provide against the possibility of the rollers being caught between the bunks, they are so spaced that the longitudinal distance between the rearmost and foremost point of each roller is greater than the greatest distance between two adjacent bunks, so that the one end of each roller always passes to and upon a bunk before it leaves the one in the rear thereof, as will be readily understood.

Other modes of applying the principle of my invention may be employed instead of the one explained, change being made as regards the means herein disclosed, provided the means stated by any one of the following claims or the equivalent of such stated means be employed.

I therefore particularly point out and distinctly claim as my invention—

- 20 1. In a base for log-loading machines, the combination with a frame, of a plurality of rollers mounted thereon and having their axes inclined relatively to the median of said frame.
- 25 2. In a base for log-loading machines, the combination with a frame structure, of a plurality of rollers mounted thereon having their axes obliquely inclined relatively to the median of said structure and parallel with each other.
- 30 3. In a base for log-loading machines, the combination with a frame, of two sets of rollers mounted thereon, the axes of the rollers of one set being inclined relatively to the axes of the rollers of the other set.
- 35 4. In a base for log-loading machines, the combination with a frame structure, of two

sets of rollers mounted upon opposite sides of a given plane, one set of such rollers having its axes inclined in one direction relatively to said plane, and the other set having its axes inclined in the opposite direction, relatively thereto.

5. In a base for log-loading machines, the combination with a frame structure including two pairs of parallel longitudinal frame members and rollers mounted between and having their axes inclined relatively to the members of each pair of such frame members.

6. In a base for log-loading machines, the combination with a frame structure comprising two pairs of parallel beams and transverse connecting members therefor, of two sets of rollers mounted between the members of each pair of beams and having their axes inclined relatively thereto, the axes of the one set of rollers being inclined relatively to the axes of the other set.

7. In a base for log-loading machines, the combination with a frame structure comprising two side beams, two beams parallel with and included between said side beams, cross-braces joining said two beams, and rollers mounted between said side beams and adjacent parallel beams respectively, said rollers projecting below the lower surfaces of said side and parallel beams.

Signed by me this 16th day of December, 1904.

JOHN R. MCGIFFERT.
